UNITED STATES PATENT OFFICE.

JAMES COSGROVE, OF FLATBUSH, NEW YORK.

BARREL.

SPECIFICATION forming part of Letters Patent No. 322,910, dated July 28, 1885.

Application filed September 22, 1884. (No model.)

To all whom it may concern:

Be it known that I, JAMES COSGROVE, a citizen of the United States, residing at Flatbush, in the county of Kings and State of New York, have invented certain new and useful Improvements in Paper Barrels, of which the following is a description.

Figure 1 is a plan view of the partly-formed blank. Fig. 2 is a plan view of the complete blank. Fig. 3 is a side view of my improved paper barrel, partly in section. Fig. 4 is an enlarged longitudinal section of one end of the barrel. Fig. 5 is a top view of one of the heads; and Fig. 6 is a side and cross section of one of the hoop strips.

My invention is designed to produce a light, strong, and serviceable barrel; and to this end it consists in the peculiar construction and arrangement of a barrel made mainly of paper, as hereinafter fully described.

In the drawings, A represents a blank sheet of stiff paper or straw board, on whose face are laid strips of veneer B B at the edges, B' in the middle, and B² B² at points representing about one-third the length of the barrel. These strips are secured by glue, and a coat of glue is then placed over the entire surface, and another sheet of paper or straw board is laid upon the same, and the whole pressed together by rolls adapted to conform to the increased thickness of the portions of the blanks where the strips are incorporated. One or more very narrow strips of pasteboard, p, are inserted on top of the thin strip of wood between each layer of paper-board or straw-board on the lines on which the two end bands are formed. When these end strips are pressed out into bands, a rim will be formed by the pasteboard projecting beyond the surface of each of the end bands just below the croze, and forming a shoulder for the edge of the head to rest upon. I drive a few nails through the bands and clinch on the other side. Then in the edges of these blanks I cut the triangular incisions a, as in Fig. 2, which reach to the strips B², or about one-third the length of the barrel that is to be formed. These strips B² thus strengthen and re-enforce the slits against tearing or splitting. The re-enforced edges B give greater strength to the ends of the barrel, and the strip B' forms a central

zone or girdle of strength to the middle of the barrel. The blank as thus formed is rolled up, its edges C C united by any suitable means, and its slit ends are then drawn together to form the taper of the barrel, and hoops placed over the ends.

In rolling the sheets of pasteboard together to form the blank, a dent or croze, a, is formed by the roller in the thickened edge B of the blank to hold the heads of the barrel. The heads H also are made of one or more layers of straw-board or paper-board. One or more rims, r, of very thin wood in layers, may be used for each head, inserted between a layer of the paper-board or straw-board which forms the head. These rims, which have a width of two or three inches from the edge of the head all around, are designed to strengthen the edge of the head when entering the croze. The said material for the heads is first run through a pair of rollers to shape the heads. They are then cut with a movable knife or knives.

The heads may be strengthened by one or more cross-bars of wood fastened to them on either the inside or outside by nailing and clinching the nails on the opposite side. I drive a few nails around the edge of the head and clinch on the other side. The hoops also are made of one or more layers of paper-board or straw-board. One or more very thin layers of wood are used for each hoop, inserted between layers of the paper-board or straw-board which form the hoop.

In making the hoops D, I cut them from a compound blank made up of alternate layers of paper and veneer, glued together. After the hoops are cut they are passed through a pair of rollers, which will shape them. By passing the hoop through these rollers the upper edge of the hoop will be made thick and the lower edge thinner, to fit the splay of the barrel. I drive a few nails through the hoops and clinch on the other side.

Instead of using only two thicknesses of paper, and intermediate strips of veneer B B', I may use a greater number of sheets of paper and a greater number of alternating strips of veneer, according to the stoutness of the barrel. I may also employ a greater or less number of re-enforcing strips around the barrel.

I am aware that it is not new to form a barrel of paper, and that a barrel has also been made of a blank whose sides were cut with gored incisions, and I make no broad claim to 5 these features; but

What I claim is—

1. A barrel-blank formed of paper with two or more re-enforcing strips of veneer incorporated in the same transversely to the barrel, 10 substantially as described.
2. A barrel-blank formed of paper with re-enforcing strips B^2 , and lateral triangular incisions extending to the said strips, as and for the purpose described.
- 15 3. A barrel-blank formed of paper with re-enforcing strips $B B' B^2$, and having lateral incisions, as and for the purpose described.

4. A paper barrel having re-enforcing strips of veneer incorporated in the same transversely to the barrel, as described. 20

5. A barrel-hoop made of alternate layers of paper and veneer rolled to a flare or taper, as described.

6. A barrel-head made of two or more layers of paper or straw board with a re-enforcing 25 rim of veneer or stiffening material incorporated between the layers at the edges, as described.

JAMES COSGROVE.
